between the electrode 3 and sheath 5 and there is no substantial collision with gas atoms, as the path is too short. In the space between the sheath 5 and the cup 2 there is very little drop in potential and hence few electrons move to cup 2 in this half cycle and their velocity would furthermore be too low for substantial bombardment of electrons from the gas atoms. There will therefore be no substantial ionic current in this half cycle and, of course, the very small electron current is negligible.

In use the tube has a starting voltage of 600 volts and a peak inverse voltage of 4 to 6 kilo volts, below which substantially no inverse current flows. The tube has been used in circuits drawing 10 micro amperes with no apparent limitation on the life of the rectifier. Much higher currents may be delivered by the rectifier with reduced life.

Having described my invention, what I claim is:

1. In cold cathode rectifiers, an envelope containing an inert gas, a cathode, an anode spaced from the cathode sufficiently to provide a path beyond the mean free path of the electrons at the pressure of said gas, and insulating material surrounding the anode all parts of which are spaced less than the mean free path of the electrons therefrom and having a multiplicity of electron paths therethrough.

2. In cold cathode rectifiers, an envelope containing an inert gas, a cathode, an anode spaced from the cathode sufficiently to provide a path beyond the mean free path of the electrons at the pressure of said gas, and a pervious sheath of insulating material surrounding the anode all parts of which are spaced less than the mean free path of the electrons therefrom.

3. In cold cathode rectifiers, an envelope containing an inert gas of low molecular weight, a cathode cup of low sputtering metal, an anode rod spaced from said cup sufficiently to provide a path beyond the mean free path of electrons at the pressure of said gas and a woven glass sheath surrounding said anode rod and in substantial contact therewith.
